UNITED STATES PATENT OFFICE.

CHARLES MILLS, OF NEWTON UPPER FALLS, MASSACHUSETTS, ASSIGNOR TO WILLIS C. SWIFT, OF CHICAGO, ILLINOIS.

MOLDING-MACHINE.

38,684.

Specification of Letters Patent. Patented Nov. 2, 1909.

Application filed May 29, 1903. Serial No. 159,235.

To all whom it may concern:

Be it known that I, CHARLES MILLS, a citizen of the United States, residing at Newton Upper Falls, in the county of Middlesex and state of Massachusetts, have invented a certain new and useful Improvement in Molding-Machines, of which the following is a specification.

My invention relates to molding machines and has for its object to provide a new and improved machine of this description.

My invention is illustrated in the accompanying drawings, wherein,

Figure 1 is a side elevation of a machine embodying my invention. Fig. 2 is an end elevation of Fig. 1.

Like letters refer to like parts throughout several figures.

In the drawings I have illustrated a simple construction embodying my invention. In this construction the stripping plate A, pattern plate B and stool plate C are arranged so that they may be all moved together and the pattern plate is also arranged so that it may be moved relatively to the stripping and stool plates. As shown in the drawings, the stripping plate A and the stool plate C are connected to the end plates, or pieces, D, in any convenient manner, as by being bolted thereto and said end pieces are arranged to move up and down in suitable guide-ways in the frame D¹ of the machine. The pattern plate B is supported upon the eccentric shaft B¹ by means of the connecting pieces B² which are provided at one end with eccentric straps B³, surrounding eccentric shaft B¹; said connecting pieces are connected at the other end to the pattern plate in any desired manner, as, for example, pins B⁴. The shaft B¹ is mounted in the end pieces D and is provided with an operating lever B⁵ so that it may be rotated to raise and lower the pattern plate. The shaft B¹ passes through a slot or opening B⁶ in the frame D¹ of the machine so that it is free to move up and down when the end pieces D are moved; said end pieces are connected by the connecting rods D² with the eccentric shaft D³ mounted upon the frame D¹, said connecting rods being provided with the eccentric straps D⁴ which surround said eccentric shaft D³. These connecting rods are preferably provided with turn buckles so that their length may be adjusted. The shaft D³ is provided with the operating le-

ver D⁵ so that it may be rotated in order to move the several plates back and forth. It is, of course, evident that other means than the eccentric shafts and associated parts may be used to secure the desired movement. The patterns B⁶ of any desired form are connected to the pattern plate and passed through suitable openings in the stripping plate A. If, for example, the patterns are of such a form as to require small sand cores such, for example, as are required in the molding of nuts, or similar devices, there will be associated with each pattern a stool C¹ which also projects through the pattern B⁶ and pattern and stripping plates as illustrated. The machine may be mounted in any desired manner, depending of course upon the use to which it is put. If, for example, it is used for molding nuts, the machine may be mounted upon a bench, or the like.

The flask E is preferably provided with beveled sides, as shown, and can be laid or rested upon a movable device such as carriage E¹, which runs on rails E², passing beneath the patterns and stripping plate, or upon a flat smooth plate. This flask opens upwardly and the sand is loosely filled therein, being heaped up above the edges. The flask is then passed under the vertically adjustable scraper F which determines the depth or amount of sand required for mold of proper density, and then on to the proper position under the machine. The patterns are then forced down into the sand to the proper depth and the sand in the flask rammed or compressed to the proper density by the patterns, stripping plate and stools, the patterns during this movement projecting through the stripping plate. The combined plates with patterns and stools and scraper F may be adjusted to secure the desired density of the sand. This movement of the stool plate, pattern plate and stripping plate is brought about by rotating the eccentric shaft D³. The rotation of this shaft by means of the eccentric straps and connecting rods moves the end plates, or supporting pieces, D, downwardly and said end plates carry with them the stool plate, pattern plate and stripping plate, and stools and patterns mounted thereon. When these plates have been moved downwardly the proper amount, to form the desired impression and compression, the patterns are drawn upwardly out of the sand through

the stripping plate by rotating the eccentric shaft B^1 . The combined plates are then raised by means of the eccentric shaft D^2 and the finished part of the mold is then moved from under the machine.

10 The stools C^1 project downwardly through the pattern and stripping plates and the patterns, forming guides for the pattern plate during its vertical movement produced by rotating the eccentric shaft B^1 . The combined plates must always be given such a movement that at the extreme of the downward movement the under surface of the stripping plate has compressed the sand 15 to the level of the upper edges of the flask. The sand is given the desired density by providing a sufficient throw for the plates and by properly adjusting the scraper F . This may be accomplished in any desired 20 manner, as by using eccentrics of different eccentricity or throw, or by adjusting the turnbuckles associated with the connecting rods D^2 .

25 A cope may be formed in a manner similar to that of the nowel as heretofore described and by placing the cope and nowel together, the complete mold is formed. This construction does away with the necessity of turning the mold over which is a 30 great advantage in cases where there are small green sand cores liable to break and fall off in the turning as, for example, in the molding of nuts and the like.

35 In the forming of sand molds the sand in the flask should be compressed to a certain density to secure the best results and when this density is ascertained or determined all of the molds should be formed with the same density. By means of my present device, the 40 proper density of the sand may be easily ascertained and when once ascertained all of the molds may be made of this uniform density. In order to secure the proper density it is necessary, as it were, to have two 45 adjustable factors: First, the depth or amount of the sand in the flask must be made adjustable, and second, the throw of the stripping plate, or, perhaps more properly stated, the compression plate, for the stripping plate is a compression plate and is used 50 for this purpose. The depth or the amount of the sand may be adjusted by adjusting the adjustable scraper F and the throw of the compression plate may be adjusted in any desired 55 manner as, for example, by the turn-buckles associated with the connecting rods of the eccentrics. It will be seen that, when once these parts are properly adjusted to secure the proper density of the sand, the flasks may 60 then be rapidly run through the machine and the sand in each flask will then have a uniform density and the best results may thus be secured without any attention whatever on the part of the operator. The compression plate must have such a throw that

when in its loose position its lower face is substantially on a level with the upper edge of the flask and hence the sand in the flask will thus be compressed so that it will be level with the upper edge of the flask. For 70 any given flask therefore after the stripping plate is properly adjusted it is only necessary to adjust the scraper to secure the desired density but the compression plate must be made adjustable so as to permit the use of 75 flasks of various sizes.

I have described in detail a particular construction embodying my invention but it is of course evident that the parts may be varied in many particulars and the construction and arrangement altered to correspond with conditions presented and that some of the parts may be omitted and others used with parts herein shown, without departing from the spirit of my invention. 80 85

I claim:

1. A molding machine comprising a stool plate, a pattern plate and a stripping plate one above the other and normally separated, the pattern plate being located between the 90 stool plate and the stripping plate, said plates connected so as to be moved together, a moving mechanism for moving said plates simultaneously in one direction, and means for moving said pattern plate with relation to 95 said stripping and stool plates.

2. A molding machine comprising a frame, a stool plate and a stripping plate rigidly connected together and movably mounted upon said frame, a pattern plate movably mounted between said stool and stripping plates, and adapted to be connected so as to move simultaneously therewith under predetermined conditions.

3. A molding machine comprising a stripping plate and a pattern plate adapted to be connected together rigidly in fixed relation to each other under predetermined conditions, means for moving said stripping plate and pattern plate simultaneously toward the 100 flask, when thus rigidly fastened together the two plates normally separated by a space, the stripping plate acting as a compression plate for the sand, and separate means for moving the pattern plate independent of the 110 stripping plate so as to withdraw the pattern from the compressed sand while the stripping plate is in position.

4. A molding machine comprising a stripping plate, a pattern plate and a stool plate 120 in different planes connected rigidly in fixed relation to each other so as to be simultaneously moved with relation to the frame of the machine, a moving mechanism for moving the pattern plate independent of the 125 stool and stripping plates, one or more stools connected with the stool plate and passing through the pattern plate, said stools acting as guides for the pattern plate during its independent movement.

5. A molding machine comprising a frame, movable pattern plate, two actuating mechanisms associated with the pattern plate, either of which when actuated causes the pattern plate to move, and separate controlling parts for said actuating mechanisms whereby either one may be operated.
6. A molding machine comprising a frame, movable support mounted on said frame, pattern plate, connected with said movable support, a moving mechanism for moving said support so as to move the pattern plate and a second separately operated moving mechanism mounted on said support for moving the pattern plate with relation to its support, both of said movable mechanisms adapted to be connected together so as to move simultaneously.
7. A molding machine, comprising a stripping plate and a stool plate rigidly fastened to the same supporting device, a frame upon which said supporting device is movably mounted, a pattern plate located between said stripping and stool plates and mounted upon a movable part, and a connection between said movable part and the supporting part of the stripping plate and stool plate arranged so that the pattern plate may be reciprocated between said stripping and stool plates.
8. A molding machine comprising a stripping plate, a pattern plate above the stripping plate, a flask located below the stripping plate, an actuating mechanism for moving the stripping plate downwardly toward the flask and a second separately operated actuating mechanism for moving the pattern plate upwardly to withdraw the pattern from the sand, said latter actuating mechanism connected with the first actuating mechanism so as to be moved when said first actuating mechanism is operated.
9. A molding machine comprising a flask, a stripping plate and a pattern plate located above said flask and normally separated from each other, said plates mounted so as to be moved in rigid relation to each other downwardly toward the flask, the stripping plate acting to compress the sand in the flask, actuating mechanism for moving said stripping and pattern plates simultaneously, a connection between the plates which prevents their relative movement during the compression of the sand in the flask, an actuating device for moving the pattern plate upwardly with relation to the stripping plate while said actuating mechanism remains stationary to withdraw the pattern from the sand while the stripping plate remains stationary.
10. A molding machine comprising a
- frame, a stripping plate and a stool plate connected to a supporting device movably mounted upon said frame, a pattern plate located between the stool and stripping plates, a controlling mechanism therefor, mounted on the supporting device for the stool and stripping plates, an auxiliary actuated mechanism connected with said supporting device, the parts arranged so that all the plates may be moved simultaneously or the pattern plate may be moved independently.
11. A molding machine comprising a frame, two supporting pieces movably mounted in said frame, a stool plate and a stripping plate rigidly connected to said supporting pieces, a shaft mounted upon said supporting pieces, a pattern plate connected with said shaft so as to be moved thereby, a second shaft mounted upon the frame of the machine and a connection between said latter shaft and said supporting pieces whereby the supporting pieces may be moved when the shaft is operated.
12. A molding machine comprising a frame, a stripping plate associated with said frame, a positive actuating mechanism for moving said stripping plate up and down, a pattern plate associated with the stripping plate, a controlling mechanism therefor mounted so as to be moved by the actuating mechanism of the stripping plate, a shaft mounted on said frame, a movable part connected with said shaft, a stripping plate connected thereto, a second shaft mounted on said movable part, and a pattern plate connected to said latter shaft.
13. A device for making molds, comprising a flask opening upward and into which the sand is loosely piled, an adjustable scraper in fixed position past which the flask is moved and which determines the height of the sand above the edge of the flask, a compression plate mounted to be vertically movable in a frame and adapted to compress the sand after its height has been determined, said compression plate adjustable so that it may be adjusted without relation to the scraper to secure the proper density of the sand in the mold.
14. A molding machine comprising a frame, a shaft mounted on said frame, a movable part connected with said shaft, a stripping plate connected thereto, a second parallel shaft mounted on said movable part, separate means for operating said shaft and a pattern plate connected to said latter shaft.
